PROGRESSIVE DISPLAY APPARATUS FOR
VISUALIZING MANUFACTURING PROCEDURES

Frank A. Lovshin, Shelton, and Warner W. Bayley, Newtown, Conn., assignors to Sidney Blumenthal & Co., Inc., New York, N. Y., a corporation of New York

Application January 13, 1948, Serial No. 2,108

5 Claims. (Cl. 35—52)

1

This invention relates to a progressive display apparatus for visualizing manufacturing procedures, and has for an object to provide means whereby a series of samples of a product at various stages of its manufacture are exhibited in such a way as to simulate to an observer progressive changes in a single sample as it is subjected to the successive steps leading to its finishing.

Another object is to provide an apparatus that includes a plurality of display units through each of which a single sample of a product is moved, each sample representing a different stage in the course of producing the product, the construction and arrangement being such as to make it appear that a single sample is being processed to completion.

Another object is to provide such an apparatus in which there is associated with each said unit a representation, preferably pictorial, of the machine or means which performs the manufacturing step that causes the change in the product displayed by the respective units.

Another object is to provide such an apparatus in which the said units are arranged in sequence with the representation of each said machine or processing means preceding the display of the sample exhibiting the result of the step performed by said machine or means.

Another object is to provide such an apparatus in which a sample is moved through each said unit by a traveling conveyor and which is so constructed that each conveyor may be readily removed, another sample attached thereto, and then be replaced, whereby different manufacturing procedures may be exhibited by the same apparatus.

Another object is to provide such an apparatus in which the construction conceals each sample and its movement except at the part of its travel designed for observation.

Another object is to provide such an apparatus which includes a series of endless belts, each belt being fitted to carry a sample, and a series of representations of machines or means for performing manufacturing steps positioned intermediate each two adjacent belts.

Another object is to provide such an apparatus which is so designed and constructed that it may readily be dis-assembled for transportation and re-assembled for display.

Another object is to provide such an apparatus which is simple in construction, of low manufacturing cost, and adapted for display without requiring other than ordinary or usual surroundings or equipment.

2

A further object is to provide certain improvements in the form, construction, material and arrangement of the several parts, whereby the above named and other objects inherent in the structure may be effectively attained.

A practical embodiment of the invention is represented in the accompanying drawing in which

Fig. 1 represents a front elevation of the apparatus;

Fig. 2 represents a top plan view thereof;

Fig. 3 represents a broken longitudinal central section, on an enlarged scale, taken in the plane of the line III—III of Fig. 2, looking toward the rear in the direction of the arrows;

Fig. 4 represents a transverse section through the whole apparatus, taken in the plane of the line IV—IV of Fig. 3, looking in the direction of the arrows;

Fig. 5 represents a similar section taken in the plane of the line V—V of Fig. 3, looking in the direction of the arrows;

Fig. 6 represents a horizontal detail section taken in the plane of the line VI—VI of Fig. 3, looking in the direction of the arrows;

Fig. 7 represents a detail transverse section on a still larger scale, taken in the same plane as Fig. 4.

Fig. 8 represents a detail side elevation, on substantially the same scale as Fig. 7, of means for maintaining the belt taut; and

Fig. 9 represents a broken horizontal section taken in the plane of the line IX—IX of Fig. 8, looking in the direction of the arrows.

It has been customary at exhibitions to display progressive manufacture of products by selecting samples of the products at various stages of manufacture and arranging them side by side in a show case, or the like, with accompanying appropriate inscriptions. This invention contemplates a major advance in this art by providing

an apparatus in which moving samples give to the observer the impression of a single sample passing through the various stages of its manufacture and thus more vividly and accurately reproduce the actual mill or factory procedure. In other words, the observer sees the raw or comparatively raw material enter the apparatus at one end and sees the finished, or comparatively finished, product exit at the other end, while

continuously witnessing the changes in the product wrought by the successive manufacturing steps to which it is subject; the effect being the same, or substantially the same, as watching the manufacturing procedure itself.

55 Referring to the embodiment of the invention

shown in the accompanying drawing, the apparatus includes a housing consisting of two sections denoted generally by 1 and 2; and having fronts 3, 4, backs 5, 6, bottoms 7, 8 and ends 9, 10. The said parts may be composed of any suitable material, such as plywood, and be secured together by any appropriate means such, for instance, as screws, some of which are shown in Fig. 1 and marked 11. When the apparatus is set up for operation the said sections are placed end to end as well shown in Fig. 1, where the line of abutment is denoted by 12.

Each section 1, 2, houses a plurality of display units, four in the present instance, and as the units are all alike and mounted in the same way, it is deemed sufficient to describe only one, selecting for this purpose that at the right end of Fig. 3. The unit includes a framework having an oblong supporting member 13 and an uprising member 14, 15, located at each end thereof. These parts may be composed of any suitable material, such as wood, and be fastened together, as by screws, not shown. The said supporting member 13 is fixed to the inside of housing back 6 by two angle brackets, preferably metallic, 16, 17, which are secured, as by screws 18 (see Figs. 4 and 5), to the said back and by screws 19 to the under surface of said member 13; while the rear edge of member 13 is also attached to back 6 by screws 20, or the like. A pair of L-shaped bearing hangers 21, 22, preferably composed of metal, have their short bent ends fastened, as by screws 23, to the underside of member 13 at the side edges thereof and about intermediate its ends, while in the lower extremities of the said hangers are formed bearings fitted to receive the trunnions 24, 25, of a belt roll 26.

Uprising member 14 carries a pair of bearing brackets 27, 28, which are preferably metallic, and are suitably secured thereto, as by screws not shown, so as to project laterally outwardly from said member 14. Said brackets are provided with slots 29, 30, which receive bearing blocks 31, 32, and expansion springs 33, 34, that normally urge the blocks outwardly (see Figs. 8 and 9); while in said blocks are journaled the trunnions 35, 36 of a second belt roll 37. Uprising member 15 carries a similar pair of bearing brackets 38, 39, which, however, are not provided with slots, springs or bearing blocks, but themselves serve as journals for the trunnions 40, 41, of a third belt roll 42.

Mounted on and near one end of each of the bottoms 7, 8, of housing sections 1, 2, is an electric motor, one of which is shown in Fig. 3 and marked 43. The motor shafts have sprockets 44 fixed thereto and similar sprockets 45 are fixed to belt roll 26 and all the other corresponding belt rolls. Chains 46, 47, connect the said motors and roll sprockets so that activation of the two motors will rotate all the said belt rolls. Endless belts 48, which may be composed of leather, rubber, fabric, etc., pass around the three rolls of each display unit, e. g. rolls 26, 37, 42; and the springs 33, 34, with their counterparts, serve to keep the belts taut to prevent slippage, which latter result may also be obtained by surfacing the belt rolls with non-slipping material such, for instance, as rubber. Thus, actuation of the motors and rotation of the rolls to which each is connected by the driving chains, will impart travel to the belts so that they move in unison.

A series of auxiliary housings, denoted generally by 49, are mounted on top of the main housing body portion, each auxiliary housing being de-

signed to cover and conceal two adjacent upper belt rolls of contiguous display units, as is well shown in Fig. 3. These auxiliary housings are similar and each includes a dome-like portion 50, a front 51 and a back 52. The fronts and backs extend downwardly along the ends of uprising portions 14, 15, of adjoining display units, to which they may be secured by screws, or the like (not shown), and abut the top edges of the fronts 3, 4, and backs 5, 6, of the sections 1, 2, of the main housing body portion; while the lower edges of the sides of the dome-like portions are fitted to rest on the front and rear parts of the top edges of said uprising portions 14, 15, but are centrally cut away to provide openings 53, which permit the belts 48 to travel therethrough.

The front of each auxiliary housing is provided with a window 54 for the purpose of presenting to an observer symbols denoting a series of progressive steps in a manufacturing procedure such, for instance, as transparent photographs of machines that perform the several steps. With particular reference to Fig. 7, it will be seen that the window is formed with an internal peripheral flange 55 and a face frame 56, which latter is screwed or otherwise suitably fastened to the front of the auxiliary housing. Intermediate the said flange and frame are positioned a sheet of frosted glass 57, a sheet of clear glass 58, and a transparent photograph 59 that is preferably colored. The arrangement is such that the frosted glass is toward the inside, the clear glass toward the outside, and the photograph between the two glasses. The frosted glass serves to diffuse the light and provide more uniform illumination. The photograph may be changed when desired by removing the frame 56 or, if preferred, removable fastening elements, such as ordinary picture frame pins, may be substituted for the flange 55. In order to supply illumination for the photograph, a pair of electric light bulbs 60, 61, of any appropriate kind and power, are fixed by brackets 62, 63, at the inside top and bottom of each window 54. The said bulbs may receive their power by suitable connections (not shown) with the source of power for the motors 43, e. g., a wall outlet box, and, of course, switches of any approved type may be provided for connecting and disconnecting the power current with the motors and the light bulbs.

Samples of material, denoted generally by 64, representing successive steps in the manufacture of an article, are secured in any proper manner to the belts 48, the arrangement and timing being such that promptly after a sample disappears through an opening 53 into an auxiliary housing 49, another sample representing the next successive step in the production of the article emerges 60 from the opposite opening 53 of the said auxiliary housing, and so on through the apparatus from one end to the other. By way of specific illustration, the production of a mohair fabric may be visualized by placing in the successive windows 65 54 photographs of machines adapted to perform the steps of scouring, combing, gilling, spinning, weaving, dyeing and finishing; and by securing to the successive belts 48, samples showing the raw mohair and the progressive changes in the same resulting from the production steps represented by the machines shown in the photographs. Whenever it is desired to change the exhibition, the fronts 3, 4, of the main housing body portion and the auxiliary housings 49 may be removed, and other belts bearing other samples

may be substituted for the belts then in the apparatus, or, if preferred, different samples may be secured to the same belts.

For the purpose of concealing the upper belt rolls located at the extreme ends of the apparatus, boxes 65, 66, are fixed, as by screws or the like, not shown, to the front 3, 4, back 5, 6, and ends 9, 10, of the main housing body portion; the said boxes being so shaped as to leave openings 67, 68 and 69, 70, for belt passage therethrough.

We have found it desirable to provide guides for the reaches of the chains 46, 47, intermediate the sprockets and several such guides are shown in Figs. 3 and 6. All the guides are alike, each consisting of a plate 71 secured to the back 5 or 6, as the case may be, of the housing sections 1, 2, by a screw 72 that pierces the central portion of the plate. A pair of rollers 73, 74, are rotatably mounted on studs 75, 76, which project from the plate 71, and each guide is so positioned that each roller 73 contacts an upper reach of a chain and each roller 74 contacts a lower reach. The said rollers are preferably spaced apart a distance less than the diameter of the sprockets 44, 45, and, by loosening the screw 72 and swinging the plate 71 in a rotary direction around the screw, the effective length of the chain contacted by the rollers may be slightly varied in order to maintain perfect meshing of the chain links with the sprocket teeth.

In operation, the selected samples are secured to the belts in the proper order and in the proper positions for sequential appearance between the auxiliary housings, the appropriate photographs are placed in the windows of the auxiliary housings, and current is supplied to the electric light bulbs and to the motors. As the belts travel their several endless paths, samples exhibiting progressive stages in the production of the selected article appear successively on the belts between the sequence of auxiliary housings, the effect upon the eyes of an observer being that of a single sample entering at one end of the apparatus as raw material and leaving at the other end of the apparatus as a finished product. If preferred, only a chosen number of manufacturing stages may be shown instead of the complete procedure from raw material to finished product. We have found a belt speed of about one inch per second to be satisfactory, and it will be clear that the motors can be run at different speeds, be provided with gear reduction, and be reversed, all at the choice of the manufacturer.

The form of the invention shown in the drawing is suited to display of the textile manufacture above described, and we have found it satisfactory to build the apparatus about twelve feet long (two six foot sections) and in about the relative proportions shown. A greater or lesser number of display units and auxiliary housings with their photographs may, of course, be provided to suit the desires of the user or the requirements of various purposes, and the invention is not limited to the textile field, but may be employed to exhibit various other procedures, e. g., in the fields of printing and chemistry.

While we have, in the foregoing description and in the drawing, referred to and shown the samples 64 as occupying but a portion of each belt 48 and as being positioned thereon so as to have the desired effect, it is quite feasible, and sometimes desirable, to provide each belt with a

plurality of pieces of material, or a single piece, sufficient to cover the whole length of the belt. For instance, a fabric weaving step may well be represented by fixing to the whole length of a canvas belt a substantial number of loops of spun yarn, and fixing to the whole length of the succeeding belt a strip of raw woven cloth or using an endless strip of raw woven cloth as the said belt itself. Hence, when we use the words sample or samples we intend that their meaning shall be construed broadly so as to include more than a single or a set of single pieces of material, and, indeed, to cover any appropriate amount or arrangement of material on the belts.

It will be understood that various changes may be made in the form, construction, arrangement and material of the several parts without departing from the spirit or scope of the invention; and hence we do not intend to be limited to details herein shown or described except as they may be included in the claims or be required by disclosures of the prior art.

What we claim is:

1. Display apparatus for progressively visualizing manufacturing procedures comprising, a housing having a body portion and a series of spaced auxiliary housings mounted along the top thereof, a series of groups of belt rolls each group being positioned partly in the said body portion and partly in a said auxiliary housing, endless belts passing around said rolls with a portion of each belt extending between adjacent auxiliary housings and exposed to view, and driving means for said rolls to cause the belts to move in unison.
2. Display apparatus for progressively visualizing manufacturing procedures comprising, a housing having a body portion and a series of spaced auxiliary housings mounted along the top thereof, a series of groups of belt rolls each group being positioned partly in the said body portion and partly in a said auxiliary housing, endless belts passing around said rolls with a portion of each belt extending between adjacent auxiliary housings and exposed to view, and driving means for said rolls to cause the belts to move in unison, said driving means being located in said body portion of the housing and engaging the rolls positioned therein.
3. Display apparatus for progressively visualizing manufacturing procedures comprising, a housing having a body portion and a series of spaced auxiliary housings mounted along the top thereof, a series of groups of belt rolls positioned partly in the said body portion and partly in said auxiliary housings, endless belts passing around said rolls with only that portion of each belt extending between the auxiliary housings exposed to view, and driving means for said rolls to cause the belts to move in unison, said auxiliary housings bearing symbols denoting different steps in a manufacturing procedure.
4. Display apparatus for progressively visualizing manufacturing procedures comprising, a housing having a body portion including a back, a series of sequentially arranged display units, each said unit embodying a supporting member, bearing hangers depending from said supporting member, a belt roll journaled in said hangers, an uprising member at each end of said supporting member, a pair of bearing brackets carried by each said uprising member, a belt roll journaled in each said pair of brackets, an endless belt passing around said rolls, means fastening each said display unit to the back of said housing

body portion to mount said units in said body portion with said uprising members and the rolls carried thereby extending above said body portion, a series of auxiliary housings mounted on said housing body portion, each said auxiliary housing concealing the belt roll carried by one uprising member of a display unit and the belt roll carried by the adjacent uprising member of the next display unit, and means located in said housing body portion engaging the rolls journaled in said hangers for driving said rolls and causing the belts to travel.

5. Display apparatus for progressively visualizing manufacturing procedures comprising, a housing having a body portion including a back, a series of sequentially arranged display units, each said unit embodying a supporting member, bearing hangers depending from said supporting member, a belt roll journaled in said hangers, an uprising member at each end of said supporting member, a pair of bearing brackets carried by each said uprising member, a belt roll journaled in each said pair of brackets, an endless belt passing around said rolls, means fastening each said display unit to the back of said housing body portion to mount said units in said body portion with said uprising members and the rolls carried thereby extending above said body portion, a series of auxiliary housings mounted on said housing body portion, each said auxiliary housing concealing the belt roll carried by one uprising member of a display unit and the belt roll carried by the adjacent uprising member of

10
